ENVELOPE

Theodore F. Philippi, East St. Louis, Ill.

Application October 27, 1932, Serial No. 639,814

2 Claims. (C. 229—72)

My invention relates to envelopes, and more particularly to a composite envelope having a compartment for comparatively bulky printed matter, such as a catalog, or the like, and a separate compartment for correspondence. It is often desirable to send out printed matter together with a letter relating thereto which is comparatively small with respect to the printed matter; and if both are mailed in an ordinary envelope of sufficient size to accommodate the bulky printed matter, it is not unlikely that the smaller letter will slip to the bottom of the envelope so that it may be overlooked by the recipient thereof. Furthermore, it is impracticable to mail out printed matter and a letter in a single envelope since letter postage would be required for the whole. In order to avoid these situations, separate letter envelopes have been pasted, or otherwise affixed, to printed matter envelopes so that the two will be received together; but, in many cases the letter is not drawn out of the envelope at the same time as the printed matter so that the two become separated in the hands of the recipient.

The principal object of this invention is to provide a composite envelope having a comparatively large compartment for printed matter and a separate compartment for correspondence which is arranged so that the recipient of the envelope is bound to withdraw both kinds of matter therefrom at the same time. Another object is to provide an envelope of this type which is simple in construction and comparatively inexpensive to make.

The invention consists principally in a composite envelope having a comparatively deep printed matter compartment and a separate, comparatively shallow letter compartment that are closed by a single flap extending from the outer mouth edge of one of said compartments with the mouth edge of the wall separating the two compartments notched below the outer edge of the other compartment. The invention also consists in the envelope, and in the parts, and combinations and arrangements of parts herein-after described and claimed.

In the accompanying drawing which forms part of this specification, and wherein like reference symbols refer to like parts wherever they occur,

Fig. 1 is a front view of a composite envelope embodying my invention,

Fig. 2 is a rear view of the envelope,

Fig. 3 is a sectional view, on an enlarged scale, 55 along the line 3—3 in Fig. 1, and

Fig. 4 is a view similar to Fig. 1 with the enclosing flap of the envelope in open position and with a portion of the front wall of the letter envelope compartment broken away to show the manner of notching the mouth edges of the envelope. 60

In the accompanying drawing, I have shown a composite envelope embodying my invention and comprising a comparatively deep printed matter envelope compartment A and a separate, 65 comparatively shallow, letter compartment B fixed on the upper front wall portion of the printed matter envelope compartment. The printed matter envelope compartment is made out of a single blank in accordance with the 70 usual practice of making envelopes; it comprises a rectangular portion 1 which constitutes the rear wall of the envelope and which has wing-like flaps 2 extending from its side edges which are folded over and pasted together to form the 75 front wall 3 of the envelope. The rear, rectangular wall portion 1 has a flap 4 extending from its bottom edge which is folded over and pasted to the front wall 3 of the envelope to close the 80 bottom thereof. The rear, rectangular wall portion 1 also has a large flap 5 extending from its upper edge which is arranged and adapted to fold over and close the mouths of both the printed matter envelope compartment A and letter envelope compartment B. 85

The letter envelope compartment is made from a separate blank and comprises a substantially rectangular, body portion 6 constituting the front wall of the letter envelope compartment and having its side edge portions 7 folded around the side 90 edges of the printed matter envelope compartment and pasted thereto so that the upper portion of the front wall of the printed matter envelope compartment constitutes an intermediate wall separating the two envelope compartments. 95 The body portion 6 of the separate blank also has a flap 8 extending from its bottom edge which is folded upwardly and pasted to the front wall of the printed matter envelope compartment to close the bottom of the letter envelope compartment. 100

The front wall portion 6 of the letter envelope compartment has its mouth edge notched as at 9. The intermediate wall separating the two envelope compartments is notched as at 10 below the bottom of the notch in the mouth edge of the front wall of the letter envelope compartment. This is an extremely important feature of my invention as will be explained hereinafter. 105 110

The flap 5 which closes the mouths of both envelope compartments is provided with a fastening device 11 which is provided with a chord 12 adapted to be wound around a second fastening device 13 provided on the front wall of the letter envelope compartment for keeping the flap in closed position. The front wall of the letter envelope compartment is also, preferably, provided with an elongated oval-shaped opening 14 which is covered with transparent material 15 to form an addressing aperture of the usual type; and also, postage stamp spaces 16 and 17 may be indicated on the letter envelope compartment and the printed matter envelope compartment, respectively, as shown in the drawing.

With my envelope, it is practically impossible for the recipient thereof to overlook either of the two kinds of matter which it is designed to carry; and the recipient of the envelope is bound to withdraw both kinds of matter at the same time. The recipient of the envelope, after opening it up, will grasp the exposed upper end portions of the two kinds of matter between the thumb and forefinger; and as the separating wall at the top of the envelope is cut away, the recipient will press the upper end portions of both kinds of matter tightly together so that he is bound to withdraw them at the same time.

My composite envelope as a whole, is of extremely simple construction, and as the greater part thereof is made in the usual manner of making ordinary envelopes, it is comparatively inexpensive to make.

Obviously, the envelope shown and described admits of variations without departing from the spirit of my invention. For instance, instead of providing the printed matter envelope compartment with the closure flap, in certain instances,

it may be feasible to provide the letter compartment with such flap; and as other changes may be desirable, I, accordingly, do not wish to be limited to the precise arrangement of parts shown and described.

What I claim is:

1. An envelope comprising a comparatively deep printed matter envelope compartment and a separate envelope wall fixed to one wall of said printed matter envelope compartment to form a comparatively shallow letter compartment with the mouths of both compartments located next to each other, the mouth edge of the wall of said printed matter compartment to which the separate envelope wall is fixed being notched below the mouth edge of said separate wall, and the other wall of said printed matter envelope compartment having a flap extending from its mouth edge adapted and arranged to fold over and close the mouths of both envelope compartments.

2. An envelope comprising a substantially rectangular blank having wing-like flaps extending from its side edges which are folded over and pasted together to form an envelope compartment and having a flap extending from its bottom edge which is folded over and pasted to the bottom edges of said wing-like flaps to close the bottom of said compartment and having a closure flap extending from its top edge, and a separate substantially rectangular blank having its side edges folded around the sides of the envelope compartment to form a separate envelope compartment and having a flap extending from its bottom edge which is folded upwardly and pasted to the wing-like flaps of the first-named rectangular blank to close the bottom of said separate envelope compartment.

THEODORE F. PHILIPPI.
